CAP

Benjamin H. Rutman, Minneapolis, Minn., assignor to Malrov-United Hat & Cap Co., Inc., Minneapolis,
Minn.

Filed Mar. 8, 1972, Ser. No. 233,002

Term of patent 14 years

Int. Cl. D2—03

U.S. Cl. D2—249

FIG. 1 is a side elevational view of a cap showing my new design, the front section being of a knitted fabric and all other sections being of other than knitted fabric;

FIG. 2 is a front elevational view thereof in the direction of the arrows 2—2 of FIG. 1;

FIG. 3 is a top plan view in the direction of the arrows 3—3 of FIG. 1; and

FIG. 4 is a fragmentary view of a second embodiment of the design, portions not shown having the same configuration as the cap of FIG. 1. FIG. 4 has been lined for color.

I claim:

The ornamental design for a cap, substantially as shown and described.
